OIL GAS PROCESS AND APPARATUS

Paul L. Born, Wilmette, Ill., assignor to The Gas
Machinery Company, Cleveland, Ohio, a cor-
poration of Ohio

Application November 22, 1948, Serial No. 61,472

9 Claims. (Cl. 48—75)

1

The present invention relates, generally, to a new and improved cyclic process of making oil gas, and to new and useful apparatus therefor.

Hydrocarbon oils have been used for many years to produce fuel gas. The development of apparatus and processes for thus using hydrocarbon oils extends back well over fifty years. The patent literature, as well as the general technical literature, discloses a rather large number and variety of forms of apparatus, and particular methods of operation, for using hydrocarbon oils or fuel oils to make various grades and types of fuel gas.

In spite of the current relatively high cost of fuel oil, the use of this material as the source of hydrocarbons for producing a high B. t. u. commercial fuel gas offers several attractive features. An oil gas process is particularly advantageous for stand-by facilities to be used intermittently to augment the supply of natural gas to a municipal gas distribution system.

The terminology, "oil gas" as used herein and in the appended claims, refers to fuel gas formed by the cracking and destructive distillation of fuel oils, and excludes the presence of any substantial content therein of gases formed from carbon or steam, or any reaction therebetween.

An important object of the invention is the provision of an efficient cyclic process of making an oil gas which is interchangeable with 1000 B. t. u. natural gas, which process can be effectively carried out in existing carburetted water gas sets with only minor modification of such existing equipment.

Since existing sets of this type comprise a substantial investment and the building of new equipment is a costly undertaking, it is an important part of my invention to be able to inexpensively convert the existing equipment to produce a gas which is interchangeable with natural gas and adaptable for use in existing consumer appliances. A better understanding of the accomplishment of this object will be gained if the limitations of existing carburetted water gas sets are understood.

About sixty years ago a process for making commercial fuel gas was brought out called the "Carburetted Water Gas" process. Briefly, it consisted of blasting a bed of hot carbon with air, forming producer gas, and burning the producer gas evolved with more air to heat the refractory brick in subsequent chambers. When the refractory filled chambers were heated to about 1400° F., the blasting was discontinued and steam was passed over the hot bed of carbon, forming

5 "Water Gas." The "Water Gas" then passed over the hot refractories in the subsequent chambers, being joined in the first refractory chamber by a stream of liquid hydrocarbon, which gasified on the hot refractories and broke up as the temperature increased into simpler and more complex hydrocarbons. The simpler hydrocarbons are called oil gas and the more complex hydrocarbons are called tar. The oil gas joins the water gas to form "Carburetted Water Gas," while the tar condenses out as liquid when the permanent gases are cooled.

10 The capacity of a standard water gas set as described above was limited by the amount of air that could be blown over the hot fuel bed of the generator per minute, because this controls the heat generated, and thereby controls the quantity of carburetted water gas that could be made later. The blasting process was exothermic, and the gas making process was endothermic. It is axiomatic that the heat developed in the blasting portion of the cycle must be equal to the heat used in the gas making portion of the cycle.

15 Standard carburetted water gas sets were customarily designed so that the producer gas made in the generator or first chamber could be completely burned and the resultant heat stored in the refractories of the second and third chambers. The upper limit to the rate of blasting is 20 the point where fuel would be blown out of the fuel bed.

25 Years of operating experience in the production of 530—565 B. t. u. carburetted water gas resulted in a balance in design of the component parts. For example, the air blasting required, after a run, to reheat the fuel bed produced just enough producer gas to reheat the refractories. Thus, a standard water gas set was developed to 30 make 550 B. t. u. carburetted water gas efficiently where the blower capacity, the generator, the carburettor, and the superheater with its checker brick was proportioned to obtain optimum conditions. Such a design requires the making of rather large amounts of carbon monoxide and this is inherent in the process.

35 The generator and carburettor were of approximately the same physical size, and the superheater contained about double the refractory brick placed in the carburettor. Three shells of the largest sets built were approximately twelve feet in external diameter, nine feet in internal diameter. The generator and carburettor were about twenty feet high, and the superheater about thirty feet high. Carburetted water gas sets thus 40 proportioned would make from three million to five

3

million cubic feet of gas per day, dependent upon the heat value and specific gravity of the gas desired.

The heating value of carburetted water gas in the manufactured gas industry ranged from about 530-565 B. t. u. per cubic foot. A typical 540 B. t. u. gas consisted of 81.5% of water gas having a heating value of 300 B. t. u. per cubic foot, and 18.5% of oil gas having heating value in the order of 1600 B. t. u. per cubic foot. The specific gravity of the finished gas ranged from 0.60 to 0.70. A typical analysis of 540 B. t. u. carburetted water gas is as follows:

CO ₂ -	6.0	15
Illum. -	9.8	
O ₂ -	0.0	
CO -	30.0	10
H ₂ -	40.0	
CH ₄ -	10.0	20
N ₂ -	4.2	
	540	
B. t. u. -	0.61	25
Sp. gr. -		

This heat value was controlled generally by the fact that carburetted water gas sets were used to make peak load and emergency supplies of gas in conjunction with the base load coal gas of approximately 550 B. t. u. per cubic foot.

About twenty years ago increasing amounts of natural gas from the Southwest began to be available for general use, and began to supersede the use of coal gas as a base load gas. This natural gas had a heat value of more than 1000 B. t. u. per cubic foot and a specific gravity of about 0.65. It therefore became necessary to produce 1000 B. t. u. gas on the peak load and emergency units. The gas utilities were faced with the problem of adapting their carburetted water gas sets (designed for 530-565 B. t. u. production) to produce 1000 B. t. u. gas, and such gas should be interchangeable with natural gas for consumers' appliances.

When a 500 B. t. u. carburetted water gas set is operated according to previous practice to make 1000 B. t. u. carburetted water gas, the efficient relationship between blower capacity, generator, carburettor and superheater size, and checker brick is disturbed. It involved radical changes in operation. First, the water gas constituent in the final gas had to be decreased to maintain a 1000 B. t. u. per cubic foot output. That is, the water gas content had to be reduced, for example, from about 81.5% at 300 B. t. u. to about 46% and the oil gas content had to be raised from about 18.5% at 1600 B. t. u. to about 54%. This affected the thermal balance of the set. The fuel bed was cooled only half as much, and the refractories twice as much as before. Furthermore, the temperature and time of contact relationship in the set for oil cracking was radically disturbed. In addition, the carbon monoxide of the finished gas adversely affected the interchangeability of the gas produced. Carbon monoxide does not have the same B. t. u. specific gravity relationship that exists in hydrocarbon gases. In effect, the carbon monoxide constituent increases the specific gravity of the finished gas, and in considering interchangeability with natural gas, carbon monoxide reduces the burner input (thru laws effecting flow thru orifices) and produces a leaner primary air mixture in burners, which results in an increased rate of flame propagation at the burner head. Further, carbon monoxide, is a much faster burning gas than the constituents of natural gas.

4

To recapitulate, the gas was not a good substitute for natural gas, and had the following defects:

(1) It had a higher specific gravity, which decreased the burner input on burners properly adjusted for natural gas. Since the primary air injection on these burners would remain the same as before, the ignition velocity of the air-gas mixture was increased due to the higher aeration.

(2) The chemical composition of this gas gave it an inherently higher ignition velocity, which, combined with the speedup of ignition velocity mentioned in paragraph (1), gave very poor burning characteristics on burners adjusted for natural gas.

Two other matters were deemed undesirable in carburetted water gas operations:

1. The presence of carbon monoxide in the gas causes it to be toxic. Elimination of carbon monoxide was deemed to be beneficial from the health standpoint.

2. A well trained personnel required to operate a fuel bed in a carburetted water gas set was very difficult and expensive to maintain on the small amount of operation found necessary for peak load and emergency service.

It will be seen, therefore, that the need, when producing 1000 B. t. u. gas, is for a method which uses efficiently the equipment built into the 550 B. t. u. carburetted water gas set, which produces a minimum of carbon monoxide, and which requires a minimum of changes in the equipment itself. Good interchangeability with natural gas must also be attained.

I have discovered the manner in which the above can be accomplished. Fundamentally, this consists of eliminating the solid fuel bed in the generator and installing a burner oil spray for heating the set in its place. Carbon monoxide is ordinarily produced by the reaction of steam on incandescent carbon. Since there is no fuel bed, no carbon monoxide can now be made in the generator. I have discovered that this spray must be installed in a horizontal position, just above the grates which are loosely covered with fire-brick, for protecting the iron from heat, so that the finely divided oil spray will spread uniformly over the area through which the blast comes from below. The space above the grate and its protective checkers in the generator then constitutes the open combustion chamber and that combustion chamber is free of checkers or bricks. In order to obtain the advantages of the horizontal spray at the lower portion of the combustion chamber it is necessary to provide means for safe ignition. This is done by using an ignition pile of refractory which will not be cooled by the incoming air blast. This ignition pile in combination with the horizontal spray is a further part of my invention. I find that in this way I can utilize the full capacity of the blower, and maintain a heat balance that will not necessitate changes in the original design proportions of the set. Steam input is such that carbon deposited in the set does not react with steam during the make period. It will be noticed that I thus utilize the existing generator and carburetor in series as originally designed, and the output of these two units in series with the superheater, also without any changes. No additional checker-brick is required in the generator to maintain this balance.

Another important object of the present invention is the provision of a cyclic process for making oil gas with substantially no attendant

formation of water gas and residual carbon, in which cyclic process there is a heating phase wherein fuel oil is completely burned in an open combustion chamber of a generator with an excess of air and the products of combustion and excess air are used uniformly to heat refractory checkers in carburetor and superheater chambers, and there is a gas making phase in which fuel oil is sprayed onto the heated checkers in the carburetor and steam is used to displace and carry off the oil gas formed in the carburetor and superheater without itself reacting with carbon that may be uniformly deposited in the checkers or otherwise being decomposed or altered to any material extent.

Another important object of the present invention is the provision of a cyclic oil gas process wherein during the heating phase, fuel oil is burned in the generator in an open combustion chamber free of refractory or checker work, except for the lining of the walls and bottom, and an excess of combustion air is used which serves completely to burn the fuel oil in the combustion chamber and also to temper or control the temperature of the refractory walls of the combustion chamber so as to prevent overheating thereof while withdrawing heat from the combustion chamber and uniformly transmitting such heat to the checker work of a carburetor and superheater connected therewith, and in addition the excess air burns off all carbon deposited in the checker work of the carburetor and superheater.

Another important object of the invention is the provision of a cyclic process of making oil gas in an apparatus comprising a generator having an open combustion chamber having a fuel oil spray located in the lower portion thereof and connected at the upper portion thereof in series with a checker-filled carburetor and a checker-filled superheater, and wherein the fuel spray in the combustion chamber may, if necessary, be used during the gas making phase as a means of cooling the refractory lining on the combustion chamber should it tend to become overheated.

Another important object of the invention is the provision of a cyclic oil gas process and apparatus therefor, wherein during the heating phase, a spray of fuel oil is ignited and burned in a generator in admixture with excess air adjacent to the bottom of a refractory lined open combustion chamber free of checkers, thereby allowing for complete combustion of fuel oil as the combustion gases rise through the chamber with the refractory lining extracting heat therefrom before the combustion gases leave the top of the combustion chamber and pass in series through checker filled carburetor and superheater units, and wherein during the gas making phase steam is passed upwardly through the generator and its open combustion chamber and absorbs heat from the refractory lining thereof which is utilized in the thermal decomposition of make oil introduced into the top of the carburetor unit, thereby making full use of the refractory lining of the open combustion chamber as a heat extracting sink during the heating phase and as a source of heat during the gas making phase.

Another object of the invention is the provision of a cyclic process and apparatus for making oil gas wherein a spray of oil is completely burned with an excess of air in a combustion chamber free of checkers or refractories which is in turn connected with a carburetor having approximately the same cubage as the combustion cham-

ber but an operative portion of which is filled with checker work or refractories.

Still another important object of the present invention is the provision of a cyclic process and apparatus for making oil gas wherein during the heating phase a spray of oil is delivered into the lower portion of an open combustion chamber of a generator so as to form a relatively thin horizontal cloud of oil spray above the bottom of the chamber, and an excess of combustion air is introduced underneath the oil spray cloud so as to sweep across the bottom of the generator and absorb heat therefrom before it rises upwardly through the combustion chamber.

Still another important object of the invention is the provision of an apparatus or set for making oil gas by a cyclic process wherein the fuel oil for heating the set is burned in an open combustion chamber of a generator with the fuel oil being introduced in the lower portion of the chamber over a relatively thin body of open checker work through which the combustion air rises, and wherein there is an upstanding body or pile of refractory disposed on said open checker work and closed to the passage of air therethrough, such refractory body or pile being heated to incandescence during the heating phase and serving positively to re-ignite the oil at the commencement of each heating phase.

Certain other objects of the invention will, in part, be obvious and will in part appear hereinafter.

For a more complete understanding of the nature and scope of my invention reference may now be had to the following detailed description of three specific embodiments thereof taken in connection with the accompanying drawings, wherein:

Figure 1 is a diagrammatic, vertical sectional view of an apparatus for carrying out my improved cyclic oil gas process;

Fig. 2 is a diagrammatic sectional view taken on line 2-2 of Figure 1;

Figure 3 is a diagrammatic, vertical sectional view of a three-shell water gas set converted in such manner than my improved cyclic water gas process may be carried out therein; and

Figure 4 is a diagrammatic, vertical sectional view of a single shell Williamson carbureted blue gas apparatus modified and adapted for carrying out my cyclic oil gas process therein.

Referring to Figures 1 and 2 of the drawings, the reference numeral 5 designates a generator having a combustion chamber 5a, the side walls and bottom of which are lined with refractory brick 6. The bottom of the generator 5 is provided with a combined air and steam inlet 7 which discharges tangentially over the bottom of the combustion chamber 5a as shown in Figure 2. The introduction of air through the inlet 7 is controlled by means of a valve 8 while the introduction of steam is controlled by means of a valve 9 in the steam connection 11.

The top of the generator 5 is provided with a dome 12 having an outlet 13 connected by a flue connection 14 to the inlet 15 in the dome 16 of a carburetor 17.

The combustion chamber 5a is provided with an oil spray or burner 18 in the lower portion thereof at a level above the air and steam inlet connection 7. The oil spray 18 is so arranged as to deliver an atomized spray of oil into the lower part of the combustion chamber so as to form a relatively flat or fan shaped cloud of oil extending across the combustion chamber.

As a precautionary measure for preventing overheating of the refractory lining in the dome 12, an oil spray 19 is desirably provided. By introducing a spray of oil at 19 during the gas making cycle the resulting spray will serve to cool the refractory lining in the dome 12.

An oil spray 20 is provided in the top of the dome 16 of the carburetor 17 for introducing oil into the carburetor over the top of the checkers therein during the gas making phase of the cycle 10 of operation.

The bottom of the carburetor 17 is open at the space 21 below the checkers and this space communicates with a corresponding space 22 underneath the checkers in a superheater 23. The top of the superheater 23 is provided with a dome 24 having an outlet connection 25. The top of the outlet connection 25 is closed by a stack valve or cover 26 which may be opened and closed by means of the mechanism 27. A fuel gas offtake pipe 28 extends at right angles from the outlet connection 25 and discharges into a wash box 30 through the connection 31 the outlet end of which extends well down into the wash box 30 and is normally submerged under the water therein. A water spray 32 may be provided in the offtake connection 28 which serves to spray a stream of water over the sides of the offtake connection 28 and the connection 31 thereby preventing formation of carbon on these metal pipes, and also to assist in cooling of the exit gas. The wash box 30 may be provided with the usual seal pot 33 and it is also provided with a gas outlet connection 34 wherethrough the fuel gas may be discharged to a holder or to a distribution system.

One of several suitable constructions for the generator 5, carburetor 17 and superheater 23 is an outer shell of steel adjacent to which is a three inch layer of insulation shielding the steel from a nine inch lining of refractory brick. An operative portion of both the carburetor and superheater is filled with checkerwork. The checker work in the carburetor 17 and in the superheater 23 may take any one of the conventional forms used for this purpose.

In operation, oil gas is made in the apparatus shown in Figures 1 and 2 as follows: The heating phase of the cyclic process is initiated by introducing air through the open valve 8 into the bottom of the generator 5 and its combustion chamber and oil into the fuel oil spray 18, this oil being ignited by suitable ignition means (not shown). The air should be introduced into the combustion chamber at a rate at least sufficient completely to burn all of the heating oil as well as all of the carbon deposited on the checkers in carburetor 17 and superheater 23. The proper rate of air introduction may readily be obtained by introducing sufficient air so that the flue gas from stack 23 will contain approximately 10% air as shown by a CO₂ analysis. As the incoming air enters the base of the generator 5 and its combustion chamber 5a it follows a turbulent path over the bottom refractory, as indicated by the arrows 35 in Figure 2, and absorbs heat from these heated refractories before rising vertically through the oil spray cloud 36 as indicated by the arrows 37 in Figure 1. The spray cloud 36 is burned with complete combustion as the gases rise through the combustion chamber 5a and by the time these gases reach the dome 12 the combustion is complete and the gases flowing over into the carburetor 17 through the connection 14 are in the form of complete combustion gases admixed with the excess of air not consumed.

The products of combustion flow downwardly through the carburetor 17 thereby heating the checkers therein with complete uniformity and thence upwardly through the superheater 23 heating the checkers therein also with complete uniformity. During the heating phase of the process the stack valve 26 is open and the products of combustion together with the excess air are discharged therethrough to the stack.

Typically, the heating period may take approximately 2.2 minutes, or about 55% of the cycle, and the checkers in the carburetor 17 and in the superheater 23 may be uniformly heated to temperatures of about 1450° F. and 1400° F. respectively.

The excess air not only insures complete combustion of the fuel oil in the combustion chamber 5a but also serves as a heat absorbing medium so as to temper the products of combustion, and, together with the heat absorbed during the gas making period, prevents the overheating of the refractory lining of the combustion chamber. Furthermore, excess air serves completely to burn out and remove deposits of carbon in the checkers formed during each gas making phase before another gas making phase is initiated. In this manner, the production of water gas is substantially entirely avoided.

After the heating phase is complete, the stack valve 26 is closed, the valve 8 is closed shutting off the air supply, and the valve 9 is opened admitting steam into the bottom of the combustion chamber 5a. The oil spray 20 is turned on, while the oil spray 18 in the combustion chamber 5a may or may not be turned on depending upon the particular conditions under which the apparatus is being operated. The steam becomes superheated as it rises through the combustion chamber 5a absorbing heat from the hot refractory lining. The steam helps carry the oil from oil spray 20 and the gaseous products formed by the cracking thereof downwardly through the checkers in the carburetor 17 and upwardly through the checkers in the superheater 23. However, the cracking or destructive distilling conditions in the carburetor 17 and superheater 23 are such that carbon deposited in the checkers is deposited uniformly. The steam itself serves only as a displacer or carrier for the oil gas formed and does not itself enter into the formation of the gas to any appreciable extent.

The fuel oil sprayed into the top of the carburetor 17 through spray 20 is usually a relatively light grade fuel oil, such, for example, as diesel oil or #2 furnace oil. If desired, tar or a relatively heavy grade of fuel oil is introduced into the oil burner 18 and burned in the combustion chamber 5a. As mentioned, this latter tar or oil spray may be maintained during the gas making phase in order to absorb part of the heat and thereby cool the highly heated refractory lining of the combustion chamber. The oil injected into the combustion chamber in the make phase is cracked therein to form hydrocarbon gases which pass with the steam into the top of the carburetor 17. The large amounts of heat stored in the refractory lining of the combustion chamber and the absence of checker work make it practical so to use heavy fuel oil and even tar in the make phase.

If during the course of operation the refractory lining of the combustion chamber 5a tends to overheat, oil may be sprayed into the combustion chamber during one or more gas making phase through either the oil spray 18 or the oil spray 19, or both if necessary. In this connec-

tion, the spray 18 serves primarily to protect the lower portion of the lining while spray 19 serves to protect the lining in the dome 12.

The fuel gas leaving the top of the superheater 23 passes through the connection 28 down through the connection 31 into the wash box 30 and leaves the apparatus through the discharge connection or elbow 34. The steam is partially condensed in the wash box and the oil gas leaving the apparatus may have the following typical composition:

Per cent by volume	
CO ₂	1.6
Unsaturated (illuminants)	21.2
O ₂	0.5
CO	1.2
H ₂	28.4
CH ₄	42.9
C ₂ H ₆	42.9
N ₂	2.3
B. t. u.	1.9
Specific gravity	0.66

When there is more blow purge, the composition may change, as follows:

Per cent by volume	
CO ₂	3.2
Unsaturated (illuminants)	23.4
O ₂	1.0
CO	2.2
H ₂	17.0
CH ₄	32.3
C ₂ H ₆	5.4
N ₂	15.5
B. t. u.	990/cu. ft.
Specific gravity	0.85

After the checkers in the carburetor 17 and superheater 23 have become cooled, the gas making phase is terminated, the apparatus is purged with air with the main air blast valve open to thereby clear the set of oil gas and then the heating phase is re-initiated. With the operating conditions during the heating phase being those mentioned above, the gas making phase may take approximately 1.8 minutes, or about 45% of the cycle.

It will be understood that the typical operating data given above in connection with the apparatus shown in Figures 1 and 2 are for purpose of illustration and a more complete understanding of the nature and scope of the invention, and are not to be interpreted in a limiting sense.

In connection with the operation of the apparatus shown in Figures 1 and 2, it will be noted that during the heating phase, no combustion of fuel oil occurs within the carburetor or superheater. This has been found to be a very important feature of the invention since it permits, and in fact insures that, the checker work in the carburetor 17 and also the superheater 23 will be uniformly heated by heat absorption from the combustion gases leaving the generator or combustion chamber 5a without placing a restriction on the amount or rate of heat input to these structures. As long as the checkerwork is thus uniformly heated, the tendency for carbon to deposit during the gas making phase is lessened and such deposits as are formed will be uniform. Thus, a serious difficulty that is ordinarily encountered in operating oil gas sets is overcome. That is, when combustion occurs in part in the checkerwork, it becomes unevenly heated and carbon deposits will be heavier in the hotter areas. Then, when the carbon is burned off these heavier carbon deposits cause local hot spots and this situa-

tion normally becomes increasingly aggravated as the process continues.

As indicated above, one advantageous feature of the present invention is the ability conveniently and economically to adapt or convert existing carburetted water gas generators from solid fuel to liquid fuel so as to take advantage of my improved cyclic process. Referring to Figure 3 of the drawings there is shown therein a standard three-shell water gas set modified for operation in accordance with my present invention. Three courses of checkers 40 are placed over the regular grate 41 to protect the same and an oil burner 42 is installed just above the checkers 40 in the lower portion of the combustion chamber 43a of the generator 43. In order to provide for re-ignition of the oil at the commencement of each heating phase, a pile or stack of refractory 39 is placed on the checker-work 40. The refractory pieces forming the stack 39 rest on a closed base so that it will not be cooled by air or steam passing therethrough. The regular air inlet 44 into the bottom of the generator 43 is provided with the usual valve 45 and the steam inlet connection 46 is provided with the usual valve 47. The usual connection between the bottom of the generator 43 and the upper portion of the checkers in the carburetor 48 is removed or blocked off. The fuel oil spray 50 into the top of the carburetor 48 is retained.

Since the refractory lining in existing installations may be rather limited in respect to the temperatures which they may safely withstand, it may be desirable to provide an auxiliary oil spray 56 adjacent to the top of the combustion chamber 43a of the generator 43 whereby fuel oil may be introduced during the gas making phase so as to cool the upper portion of the generator.

It will be seen that the apparatus shown in Figure 3 may be operated generally in the same manner as the apparatus described above and shown in Figures 1 and 2. That is, there is a heating phase in which air is introduced into the bottom of the generator 43 and flows upwardly through the protective brick work 40 to burn the spray or cloud of oil admitted through the oil burner 42 in the combustion chamber 43a above the protective brickwork 40. An excess of air is used and the products of combustion together with the unconsumed air pass over to the carburetor 48, downwardly therethrough, and then upwardly through the superheater 51 thereby heating the checkers in both units. The combustion gases leave the apparatus through the open stack valve 52. After the heating period has been complete, the stack valve 52 is closed and the air supply valve 45 is also shut off and the steam valve 47 is opened. At the same time the oil spray 50 is established and the steam flows upwardly through the generator 43 becoming superheated as it draws heat from the walls and bottom thereof and then passes over to and downwardly through the carburetor 48 and then upwardly through the superheater 51. The steam serves as a carrier or displacer for the oil gas generated in the carburetor and superheater. Oil gas leaves the superheater from the top through the connection 53 and discharges into the usual wash box 54 from which it leaves through the elbow connection 55. If desired, the oil spray 42 may be continued during the gas making phase of the cycle in order together with the excess air supplied during the heating phase, to control the temperature of the refractory lining of

11

the generator 43 thereby preventing the over-heating of the same.

After each make-phase is complete, the apparatus is purged of oil gas by the air blast and then the oil burner 42 is re-ignited by the incandescent refractory stack or pile 39.

When operating a 550 B. t. u. carburetted water gas set to produce 1000 B. t. u. oil gas by the process herein described, I have described that the thermal capacity of the set is doubled, the labor problem is reduced, and carbon monoxide in the resulting gas is largely eliminated. This gas can be substituted nearly 100% for natural gas. A typical gas analysis follows:

CO ₂	2.2	15
III	23.6	
O ₂	0.8	
CO	1.4	
H ₂	22.2	10
CH ₄	42.0	
C ₂ H ₆	2.1	
N ₂	5.7	
	100.0	
B. t. u.	1023	
Sp. gr.	0.73	
Refractory temperature	°F 1600	

When better grades of oil can be obtained for feed stock, better interchangeability can be obtained, due to further reduction in carbon dioxide, carbon monoxide and nitrogen.

This method of converting a standard water gas process to an oil fired oil gas process is generally distinguished as follows:

1. Low investment cost of conversion.
2. Improvement of gas burning characteristics, due to the elimination of carbon monoxide.
3. The same relative costs of manufacture per therm.

4. Reduction of labor problem.

In Figure 4 of the drawings there is shown a Williamson single shell carbureted blue gas apparatus converted in such manner as to operate in accordance with the present invention. Protective checkers 60 are installed above the grates 61 and an oil burner 62 is installed just over the protective checkers 60 in the lower portion of the combustion chamber 58 of the generator 57. An ignition pile 60a having a closed bottom and resting on the protective checkers 60, in a manner and location similar to the pile 39 of Figure 3, is employed for automatic ignition purposes. In operation, in the heating phase, primary air is introduced through the air supply connection 63 through the open valve 64 and flows upwardly through the protective checkers 60 to burn the oil spray introduced by the burner 62 in the combustion chamber 58. The products of combustion flow upwardly through the combustion chamber 58 of the generator heating the refractory walls thereof and thence pass upwardly through the outside flue pipe or connection 65 leading to a vertical connection 66 leading into the top of the carburetor chamber 67. An excess of air is passed upwardly through the generator and the products of combustion together with the unconsumed air serve uniformly to heat the checkers in the carburetor chamber 67 as well as the checkers in the superheater chamber or section 68. A portion of the excess air may be introduced through what originally was a secondary air valve 59, so as to give a greater cooling effect to the refractory lined flue

12

65. During the heating period the stack valve 70 is opened allowing the gases to pass upwardly through the stack 71.

After the heating phase is complete, the stack valve 70 is closed, the air supply valve 64 is closed and the steam valve 72 leading into the bottom of the generator 57 is opened. The steam sweeps upwardly through the generator 57 and its combustion chamber 58 absorbing heat therefrom and enters the carburetor 67 through the top thereof. At the same time the oil spray 73 is opened which serves to spray fuel oil on top of the checkers in the carburetor 67. The steam sweeps the oil gases formed from the fuel oil downwardly through the carburetor 67, upwardly through the superheater 68 and thence out through the gas offtake 74. The gas offtake 74 discharges into the usual wash box 75 and leaves the same through the outlet connection 76.

In order to protect the refractory lining in the top of the generator, it is desirable to provide an auxiliary oil spray 77 through which oil may, when necessary, be sprayed during the gas making phase.

25. It will be noted that the cubage of the carburetors in the apparatus shown in Figures 3 and 4, exclusive of the checkers therein, is approximately equal to the cubage of the respective generators. Even though the apparatus is operated in a cyclic manner and steam is used in the gas making phase to carry out and displace the fuel gas generated, substantially no other gas is formed during the operation except for the small amount of "blow-purge gas." Such carbon as is uniformly deposited in the checkers during the gas making phase is rapidly and completely burned off during the initial portion of the following heat phase without production of local hot spots. It will thus be apparent that 30 the operation of the apparatus shown in Figures 3 and 4 is generally the same as that described in detail above for the apparatus shown in Figures 1 and 2.

The protective refractory checkers 40 (Figure 3) and the protective refractory checkers 60 (Figure 4) become highly heated during operation of the respective converted carbureted water gas generators thereby permitting use of heavier oil and tar for firing and also permitting utilization of ignition piles such as 39 (Figure 3) or 60a (Figure 4).

Automatic control equipment of known type may be used to control the operation of the cyclic process.

55. It will be understood that the cyclic process of the present invention may be adapted to other types of gas making apparatus and that the specific embodiments described above are given by way of illustration with the understanding that the invention may be practiced in other embodiments.

Having fully described my invention, what is claimed as new is:

1. In a standard three-chamber carburetted water gas set which has a generator with a combustion chamber and a carburetor, and a superheater, with the outlet of the combustion chamber connecting with the inlet of the carburetor chamber and the outlet of the carburetor chamber connecting with the inlet of the superheater chamber and with said last two chambers each having an operative portion filled with checkers, and a grate in the lower portion of said generator beneath said combustion chamber and air and steam inlets in the base of the generator beneath

the grate, the improvement which comprises a cover of checkers on the grate at the bottom portion of the combustion chamber to protect the grate, a fuel oil spray adjacent the inner vertical wall in the lower portion of the combustion chamber above the protective checkers adapted to discharge a horizontal spray across the lower portion of the combustion chamber in place of using solid fuel and thereby to permit an open combustion chamber, and refractory ignition means located in said combustion chamber inwardly from the wall and above said protective checkers in line with the fuel oil spray, whereby the set may produce gas having a calorific value and specific gravity making it interchangeable with natural gas of approximately 1000 B. t. u. per cubic foot.

2. The improvement set forth in claim 1 wherein the ignition means comprises a refractory pile disposed directly on the protective checkers and provided with a closed base so that it will not be cooled by the upward passage of air or steam through the pile.

3. The improvement set forth in claim 1 wherein the fuel oil spray substituted for solid fuel provides a relatively thin fan-shaped cloud of oil which is sprayed across the combustion chamber in a horizontal plane above the protective checkers.

4. The cyclic process of making oil gas which is interchangeable with natural gas having approximately 1000 B. t. u. per cubic foot with substantially no attendant formation of water gas in a standard three-chamber water gas set which has a refractory lined generator having a grate and a combustion chamber formed above the grate with the combustion chamber and carburettor chamber being interconnected with the outlet of the combustion chamber connecting with the inlet of the carburettor chamber and the outlet of the carburettor chamber connecting with the inlet of a superheater chamber and with said last two chambers each having an operative portion filled with checkers, which set originally produced carburetted water gas having a calorific value of from 530 to 565 B. t. u. per cubic foot, said process comprising forming a relatively thin horizontal spray of fuel oil above the grate in the lower portion of the open combustion chamber which is free of checkers, introducing an excess of combustion air into the bottom of said generator to flow upwardly through said grate into the combustion chamber cross current to said oil spray to provide an intimate intermixing and combustible mixture of the oil and air above said grate at the bottom portion of said combustion chamber, completely burning said oil spray with said excess combustion air in said combustion chamber and heating an ignition pile in the combustion chamber to incandescence so that it will serve positively to re-ignite the oil at the commencement of the next heating phase, passing the products of combustion together with unconsumed excess air through said carburettor and then through said superheater, thereby uniformly heating the checkers therein to oil gas making temperatures in the neighborhood of 1400° F. to 1800° F. and at the same time burning off any deposits of carbon that may have been deposited on the checkers during the preceding gas making phase, said excess air being sufficient to temper the products of combustion sufficiently to protect the refractory lining of said combustion chamber from overheating, discontinuing said introduction of

air and fuel oil into the combustion chamber after said checkers have been sufficiently heated for oil gas making, thereby completing the heating phase of said cyclic process, and then commencing the gas making phase by introducing steam into the bottom of said generator beneath the grate and thence through the combustion chamber and spraying oil into the carburettor at a place adjacent the inlet thereto, said steam absorbing heat from the walls of said chamber as it passes therethrough and being introduced in sufficient volume to sweep up through said combustion chamber and thence through said carburettor and superheater so as to displace and carry away the oil gas formed and fixed in said carburettor and superheater, respectively, without itself being decomposed to any substantial degree, discontinuing said steam introduction and said spray of oil into said carburettor after said checkers have become cooled to a predetermined temperature, and purging the apparatus of oil gas by an air blast preparatory to initiating another heating phase, thereby completing one cycle of said cyclic process.

5. The process of claim 4 wherein a relatively heavy grade of fuel oil is sprayed into said combustion chamber and a relatively light grade of fuel oil is sprayed into said carburettor during the gas making phase.

6. Apparatus for making oil gas, comprising a refractory lined, vertical generator having an open combustion chamber substantially free of checkers, a carburetor and a superheater each having an operative portion filled with checker bricks and interconnected in series relation whereby exit gases leaving said combustion chamber enter the inlet of said carburetor and exit gases leaving said carburetor enter the inlet of said superheater, said combustion chamber being provided with oil burner means in the lower portion thereof but at a level substantially above the base of said generator, air and steam inlets discharging into the base of said generator beneath the oil burner means whereby air and steam introduced therethrough flow over and in contact with the base of said generator prior to rising upwardly therethrough, and ignition means located in said combustion chamber inwardly from the wall and disposed at a horizontal level corresponding to that of the oil burner means.

7. In apparatus for making oil gas which has a generator with a combustion chamber and a carburetor and a superheater, with the outlet of the combustion chamber connecting with the inlet of the carburetor chamber and the outlet of the carburetor chamber connecting with the inlet of the superheater chamber and with said last two chambers each having an operative portion filled with checkers, and a grate in the lower portion of the generator beneath said combustion chamber but substantially above the base of the generator and air and steam inlets in the base of the generator beneath the grate, the improvement which comprises checkers on the grate only to a depth sufficient to protect the grate with said combustion chamber being entirely open thereabove, and a fuel oil spray having a horizontal delivery adjacent the inner vertical wall of the combustion chamber above the protective checkers at the bottom of the combustion chamber for discharging a horizontal spray of oil across the bottom portion of the combustion chamber in place of using solid fuel, said checkers on the grate being so disposed on said grate as to distribute evenly and cross-wise of the hori-

zontal spray of oil the incoming air from the base of the generator for providing an intimate intermixing and combustible mixture of excess air and oil at the bottom of the open combustion chamber of the generator so that the entire open combustion chamber is used in producing complete combustion of the oil before the products of combustion and excess air leave the combustion chamber to cross over to the carburetor chamber.

8. The apparatus of claim 7, together with a fuel oil spray adjacent the inner wall of the combustion chamber of the generator adjacent the top of said chamber, the fuel oil spray at the bottom of the combustion chamber above the grate and the fuel oil spray at the top of the combustion chamber being adapted to be used, during the gas making phase of the apparatus, for reducing undesired excessive temperatures of the whole length of the refractory walls of the combustion chamber.

9. In the process of making oil gas which is interchangeable with natural gas having approximately 1000 B.t.u.'s per cubic foot with substantially no attendant formation of water gas in a three-chamber set which has a refractory lined generator having a combustion chamber above the bottom of said generator, a carburetor chamber and a superheater chamber, with the outlet of the combustion chamber communicating with the inlet connection of a carburetor containing checkers, and with the outlet of the carburetor chamber connecting with the inlet of a superheater containing checkers, an improved process of heating which comprises forming a relatively thin fan-shaped horizontal spray of fuel oil in the lower portion of the combustion

chamber but at a level substantially above the bottom of said generator, introducing an excess of combustion air into the bottom of said generator and underneath said oil spray, said air being thereby heated before being flowed upwardly cross-current to said thin horizontal spray of fuel oil for providing an intimate intermixing and combustible mixture of said air and oil across the lower portion of said combustion chamber, completely burning said mixture of oil spray and excess combustion air in said combustion chamber which is open along its length, passing the products of combustion, together with unconsumed excess air, from said open combustion chamber through said carburetor and then through said superheater, thereby uniformly heating the checkers therein to oil gas making temperatures in the neighborhood of 1400° F. to 1800° F. and at the same time burning off any deposits of carbon that may have been deposited on the checkers during the preceding gas making phase.

PAUL L. BORN.
